Primary Examiner—Janice E. Seeger

[57] CLAIM

The ornamental design for a picture frame, as shown and
described.

DESCRIPTION

FIG. 1 is a perspective view of a picture frame showing my
new design;

FIG. 2 is a front view thereof;

FIG. 3 is top view thereof, the bottom view being identical;

FIG. 4 is a left side view thereof, the right side view being
identical;

FIG. 5 is a perspective view of a second embodiment of a
picture frame showing my new design;

FIG. 6 is a front view thereof;

FIG. 7 is a top view thereof, the bottom and side views being
identical; and,

FIG. 8 is a left side view thereof, the right side view being
identical.

The rear view of each embodiment forms no part of the
claimed design. The broken lines shown in FIGS. 1, 3, 4, 5,
7 and 8 represent environmental subject matter and form no
part of the claimed design.
